UNITED STATES PATENT OFFICE.

PRESTON L. ANDREWS, OF BROOKLYN, NEW YORK.

ENVELOPE-FASTENING DEVICE.

Application filed April 26, 1922. Serial No. 556,583.

To all whom it may concern:

Be it known that I, PRESTON L. ANDREWS, a citizen of the United States, residing at Brooklyn, in the county of Queens and State of New York, have invented certain new and useful Improvements in Envelope-Fastening Devices; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to an improved construction and arrangement of envelope fastening means. The invention has for its principal object to provide an improved construction of metallic clasp or fastener for envelopes of the kind having laterally projecting arms capable of being upturned to pass through a perforation in the envelope flap, and then bent back to extend over the marginal portions surrounding the said perforation to thereby retain the flap in closed position. To this end the arm or arms are formed in such a manner as to assure their bending at points adjacent to the juncture of the arms with the main body or support of the fastener, thus preventing undue or undesired deformation of the arms, and predetermining the bending points to the end that, when up-turned, the arms will readily and easily pass through the perforation of the flap.

Another object of this invention is to provide an arrangement of metallic fastener for envelopes of such form that the tips of the fastener arms are normally inclined or bent downwardly from the plane of the main portion of the arm, so that the same may offer a minimum of projection above the plane of the flap when turned downwardly over the latter, thus reducing the likelihood of the extremities of the arms being accidentally engaged and lifted whereby the arms are removed from their most efficient fastening position. In this connection it is also the object of this invention to provide reenforcing members or discs surrounding the flap perforations, which are formed to cooperate with the downwardly bent tips of the fastener arms to further guard the latter against accidental displacement or lift once

they are bent down in holding relation to the envelope flap.

Other objects of this invention, not at this time more particularly enumerated, will be clearly understood from the following detailed description of the same.

The invention is clearly illustrated in the accompanying drawings, in which:—

Figure 1 is a rear face view of an envelope and its flap provided with the novel fastening means made according to and embodying the principles of this invention; Figure 2 is a detail vertical section, taken on line 2—2 in Figure 1, but drawn on an enlarged scale; Figure 3 is a detail fragmentary section of the envelope flap and reenforcing discs, showing the free end of the fastener arm as operatively related to the outer disc, said view being drawn on a further enlarged scale; Figure 4 is a view similar to that shown in Figure 2, but illustrating the flap reenforced by a disc on the outer side only; Figure 5 is a fragmentary rear face view of an envelope and its flap, the latter having a modified form of reenforcing disc for cooperation with the fastener, and Figure 6 is a vertical section through the same, taken on line 6—6 in Figure 5 and drawn on an enlarged scale; Figure 7 is a fragmentary rear face view of an envelope and its flap, the latter having still another modified form of reenforcing disc for cooperation with the fastener, and Figure 8 is a vertical section through the same, taken on line 8—8 in Figure 7, and drawn on an enlarged scale; Figure 9 is a fragmentary rear face view of an envelope and its flap, showing the fastener in operative relation thereto, but the flap reenforcing discs being omitted; and Figure 10 is a perspective view of the metallic fastener alone, drawn on an enlarged scale.

Similar characters of reference are employed in all of the hereinabove described views, to indicate corresponding parts.

Referring now to said drawings, the reference character 11 indicates an envelope body provided at its open end with a flap 12 adapted for folding over said open end upon the back of said body. Said flap is provided with a suitably placed perforation or hole 13. Adhesively and respectively secured to the outer and inner faces of said flap is an outer perforate reenforcing disc 14 and an inner perforate reenforcing disc 15, which have their perforations registered

or aligned with the flap perforation or hole 13, and which are adapted to reenforce the marginal portions of the flap surrounding said perforation or hole 13. Said discs 14 and 15 are preferably made of paper, but the same may be made of other suitable material if desired.

The novel metallic fastener comprises a main portion or base 16, preferably having 10 a tubular shank 17 projecting downwardly therefrom adapted to be passed through the body of the envelope and riveted or upset over the inner side of the body, as at 18, to secure the fastener to said envelope body. 15 Integrally formed in connection with said main portion or base 16, so as to project outwardly from the rim or periphery thereof, are one or more fastener arms 19 which normally lie substantially in the horizontal 20 plane of said main portion or base 16. Said arms 19 are widest at their inner ends, as at 20, the sides 21 tapering or converging toward their outer extremities. The wide inner ends 20 are integrally joined to said 25 main portion or base 16 by restricted necks 22 of substantially reduced width relative to the wide inner ends 20 and said main portion or base 16, thus reducing the amount and area of metal at the juncture of said 30 arms 19 with the main portion or base 16, and thereby establishing a point of bend, so that when up-turned the arms will bend relative to said main portion or base 16 at said restricted necks 22, since said points, 35 by reason of the reduced amount and area of metal there provided, offer the least resistance to the bending operation, and therefore assure that the arms 19 will bend uniformly upwardly at such points without danger of 40 otherwise unduly deforming the main bodies of said arms. Said arms 19 terminate at their outer extremities in downwardly inclined or bent tip portions 23, thus normally projecting the ends of the arms 10 toward the envelope flap, when said arms are normally bent 45 downward to flat holding relation to the flap.

In most cases it is desirable to make the outer reenforcing disc 14 of a diameter somewhat greater than the longitudinal spread of the fastening arms 19, when the latter are turned down to fastening position, and then providing in the outer surface of said reenforcing disc 14 countersunk seats or depressions 24, into which the downwardly inclined tip portions 23 of the arms 19 will be received. When said tip-portions are thus disposed relative to the seats or depressions 24, the ends of the arms 19 are guarded 50 against being caught or subjected to accidental engagement whereby accidental force is applied thereto tending to lift or bend upwardly the arms from normal fastening position. Any article or mail matter sliding 55 against the ends of the arms 19 thus guarded

will meet the downwardly inclined outer face of the tip-portions 23 and will be shunted away without danger of catching the arm and accidentally straining the same upward. This arrangement is of distinct 70 advantage for envelopes used for mailing purposes, since it practically insures against accidental breaking off of the fastener arms or a bending of the same to an extent likely to permit the flap to pull away therefrom 75 and thus open the envelope.

In Figure 4 I have illustrated an envelope, and its perforated flap, provided with my novel metallic fastening means, but showing the employment of only the outer reenforcing disc 14. In operation and construction this form is otherwise the same as above described.

In Figures 5 and 6 I have illustrated an envelope, and its perforated flap, provided with my novel metallic fastener, but showing a modified form of reenforcing disc surrounding the perforation of the flap. In this case instead of employing an outer reenforcing disc of greater diameter than the spread of the arms of the fastener, as was the disc 14 above described, I provide an outer reenforcing disc 25 of less diameter than the spread of the arms 19 of the fastener, so that the downwardly inclined or bent tip-portions 23 of said arms 19 project beyond the periphery of the disc 25 to incline downwardly to the body of the envelope flap. This arrangement of the tip-portions places the same below the plane of the disc face, and the periphery of the disc together with the inclined face of the tip-portion serve to guard the arm 19 against being caught and accidentally lifted out of normal holding relation to the flap.

In Figures 7 and 8 I have shown an envelope, and its perforate flap, provided with my novel metallic fastener, but showing in connection therewith a still further modified form of reenforcing disc surrounding the perforation of the flap. In this case I employ an outer reenforcing disc 26 of a diameter approximately equal to the spread of the arms 19 of the fastener. This disc 26 is provided in its periphery with indented portions or notches 27, so that when the arms 19 are turned down across the face of the disc, the tip-portions 23 of said arms will be disposed within the said indented portions or notches 27, whereby the outer ends of the arms are guarded against accidental engagement by anything tending to lift the arms out of normal holding relation to the flap.

It is in some cases desirable to employ my novel metallic fastener with envelopes having a flap provided with a suitable hole or perforation from about which the reenforcing discs are omitted, an example of this arrangement is shown in Fig. 9. Even in

this case the downwardly inclined tip-
portions 23 of the arms 19 tend to resist and
shunt off the accidental engagement there-
with of anything tending to lift the arms 19
out of normal holding relation to the flap.

From the above description it will be ap-
parent that my present invention not only
provides a novel metallic fastener per se for
envelopes, but also provides in combination
10 with such fastener novel means for further
guarding the same against accidental dis-
placement once the fastening arms thereof
are firmly pressed down into normal hold-
ing engagement with the envelope flap.

15 I am aware that some changes may be
made in the various arrangements and com-
binations of the several devices and parts
without departing from the scope of my in-
vention as above set forth and as defined in
20 the appended claims. Hence, I do not limit
my invention to the exact arrangements and
combinations of said devices and parts as
hereinabove set forth, nor do I confine my-
self to the exact details of the construction
25 thereof as shown in the accompanying
drawings.

I claim:—

1. The combination with an envelope and
its perforate flap, of a perforate reenforcing
30 disc secured to said flap in registration with
the perforation of the latter, a metallic
fastener, comprising a base having means
for securing the same to the envelope body
beneath the flap and alined with the per-
35 foration thereof, fastener arms integrally
connected with said base to extend out-

wardly from the periphery thereof and nor-
mally disposed in the plane thereof, the
free extremity of said arms terminating
in downwardly inclined tip-portions; and
40 said reenforcing disc having suitably dis-
posed recesses to receive said downwardly
inclined tip-portions.

2. The combination with an envelope and
its perforate flap, of a perforate reenforcing
45 disc secured to said flap in registration with
the perforation of the latter; a metallic
fastener, comprising a base having means
for securing the same to the envelope body
beneath the flap and alined with the per-
50 foration thereof, fastener arms extending
in opposite direction from and normally
disposed in the plane of said base, each
arm having at its inner end a neck portion
of reduced width integrally joined with the
55 periphery of said base, said neck portions
being adapted to reduce the amount and
area of metal at the juncture of said arms
with said base to thereby establish the bend-
ing points of said arms, the free extremities
60 of said arms terminating in downwardly in-
clined tip-portions; and said reenforcing disc
having suitably disposed recesses to receive
said downwardly inclined tip-portions.

In testimony that I claim the invention
set forth above I have hereunto set my
hand this 14th day of April, 1922.

PRESTON L. ANDREWS.
